DETACHABLE MEANS FOR HOLDING SEPARATE DEVICES EMPLOYED IN PROCESSING MOTION-PICTURE FILM IMMOVABLE RELATIVE TO ONE ANOTHER

Philip Baia, Highland Park, Mich.

Application November 15, 1952, Serial No. 320,800

3 Claims. (Cl. 88—1)

1

This invention relates to detachable means for holding separate devices employed in processing motion picture film immovable relative to one another. At the present time it is customary to permanently secure rewind devices upon a board or other rigid member in correct spaced relation, usually with a viewer also mounted thereon between the said rewind devices. However this practice is open to a number of objections. For instance, while each separate device by itself is sufficiently small and compact to be easily handled or readily packed for storage when not in use, it is not only much more difficult to handle or store the entire assembly, but it is also far harder to adequately protect the separate parts when so mounted against dust and dirt.

This invention aims, among other things, to provide means both integral with the devices themselves and removable from them for securing the separate devices in correct spaced relation to one another, to the end that when use of the devices in combination is no longer required they may be quickly and easily disassociated from one another so that each device may be separately moved, packed or stored independently of each other device.

Having thus briefly stated the general purpose of the invention, and the advantage thereof, I will now describe it in detail with the aid of the accompanying drawing, in which:

Figure 1 is a plan view showing an assembly including a viewer, and a rewind device secured in spaced relation thereto on each side thereof.

Figure 2 is a front elevation of Figure 1.

Figures 3 and 4 are enlarged sections on the lines 3—3 and 4—4 respectively of Figure 2.

Figure 5 is a modification in so far that only two rewind devices are shown held in spaced relation to one another by a single spacer element.

In Figures 1 to 4, inclusive, the invention is shown as applied to one known form of viewer 1, such as that disclosed in my United States Patent No. 2,422,816, for holding it in spaced relation between two conventional rewind devices 2, such as the one shown in my United States Patent No. 2,555,671.

The film viewer 1 consists in part of a stand 3 having a lens mounting 4 thereon to support a lens 5 across which a film 6 passes. The film is guided in its passage across the lens 5 by guides 7 mounted on opposite sides of the mounting 4. Each rewind device consists in part of a stand 8 on which a spindle 9 is rotatably sup-

2

ported, and carried on each spindle for rotation therewith in a spool 10 around which one extremity of the film 6 is wound.

Formed integral with the stand 3 of the optical film viewer 1 and extending inwardly from opposite sides thereof are aligned tubular socket members 11, the axes of which are parallel with the path of movement of the film 6 between the guides 7, and removably mounted in each tubular member 11 is one extremity of a spacer element 12. A stop 13 is provided in each socket member 11 for limiting the distance an element 12 may be inserted so that when one extremity of an element rests against each stop the opposite extremity projects a predetermined distance from its socket member 11. Formed vertically through the stand 3 and projecting into the bore of each annular member 11 is an aperture 14 the inner portion of which is threaded and smaller in diameter than its outer portion. Formed through each spacer element 12 adjacent each extremity is a radial opening 15; moreover the opening in one extremity of each element is at right angles to the opening in the opposite extremity. The opening 15 in one extremity of each element 12 registers with one of the apertures 14, and engaging the threaded portion of each aperture is a screw 16 having an axial projection 17 of reduced diameter which extends into one of the openings 15 and thus holds one tubular element immovable in its member 11. It will also be noted that in order to facilitate engagement of the openings 15 by the projections 17, the latter are made long enough to extend into the openings 12 prior to engagement by the screws 16 with the threaded portions of the apertures 14.

Integral with the stand 8 of each rewind device 2 is a tubular socket member 18 which extends inwardly from one side of the device and at right angles to the axis of the spindle 9 rotatably supported thereon. Extending into the bore of each tubular socket member 18 at a predetermined distance from the adjacent side of the stand is a stop 19. Formed horizontally through each stand 8 and extending substantially radially through its socket member 18 is an aperture 20 the inner extremity of which is threaded and smaller in diameter than its outer extremity. Extending into each tubular socket member 18 is the extremity of one of the spacer elements 12 remote from the optical viewer 1. The opening 15 through that extremity of each spacer element is positioned to register with one of the apertures 20 when the adjacent end of

that element is in contact with one of the stops 19. A screw 21 engages the thread in each aperture 20 and has an axial projection 22 thereon of reduced diameter which enters one of the openings 15 and holds that spacer element immovable relative to that rewind device 2.

It will therefore be seen that by the insertion of the spacer socket members 12 into the tubular elements 11 and 18, and by securing the said elements in position with the screws 16 and 21 the assembly is quickly made, and so made that the separate parts may be quickly and easily detached from one another and from the spacer elements when desired for storing or packing.

In the modification shown in Figure 5, the arrangement is the same except that the optical viewer is omitted and two rewind devices 2 having stands 3 are held in spaced relation by a single spacer element 12a the ends of which extend into tubular socket members 18a integral with the said stands. When the ends of the elements 12a are in contact with stops 19a in the socket members 18a the said elements are positioned for engagement by screws 21a in exactly the same manner as above described.

While in the foregoing the preferred embodiments of the invention have been described and shown, it is understood that alterations and modifications may be made thereto provided the said alterations and modifications fall within the scope of the appended claims.

What I claim is:

1. A demountable film viewer device comprising an optical viewer including a stand having a lens mounting thereon and means on opposite sides of the mounting for guiding a film during its passage between them, a tubular socket member integral with the stand extending inwardly from each side thereof and parallel with the path of the film between the guide means, a film rewind device spaced from each side of the optical viewer, each rewind device including a stand having a spindle rotatably mounted thereon and means on the spindle for supporting a spool for rotation therewith whereby the film may be viewed as it passes from one spool to the other spool, a tubular socket member integral with each rewind stand and extending from one side thereof at right angles to

the axis of the spindle thereon, a spacer element having one extremity detachably mounted in each tubular socket member on the optical viewer and its opposite extremity detachably mounted in the tubular socket member on one of the rewinding devices, said spacer element adapted to align said film guides with the spool elements, and means at the lower end of each stand detachably engageable with the adjacent end of the spacer for preventing accidental disengagement of each extremity of each spacer element from the tubular socket member in which it is mounted.

2. A demountable film viewer as in claim 1, wherein said means includes the provision of an aperture in each stand radial to the longitudinal axes of said socket members and extending into the bores of said socket members, portions of all of said apertures being threaded, and a screw in threaded engagement with each aperture holding one extremity of one spacer element immovable.

3. A demountable film viewer as in claim 1, wherein said means includes the provision of an aperture in each stand radial to the longitudinal axes of said socket members and extending into the bores of said members, the inner portions of all of said apertures being threaded and smaller than their outer portions, each spacer element having a radial opening therein adjacent each extremity, a screw in threaded engagement with the thread in each aperture, an axial projection on each screw engaging in the openings in one spacer element, said projections being of such length that they engage the openings prior to engagement of the screws with the threads in the apertures and an abutment element in each tubular socket member for limiting the movements of each spacer element into its tubular socket member.
